UNITED STATES PATENT OFFICE

122,000

DESIGN FOR AN ELASTIC WEB FABRIC

Norman E. Randall, Shannock, R. I., assignor to
Columbia Narrow Fabric Company, a voluntary
association of Rhode Island

Application June 18, 1940, Serial No. 93,080

Term of patent 14 years

To all whom it may concern:

Be it known that I, Norman E. Randall, a citizen of the United States of America, residing at Shannock, county of Washington, State of Rhode Island, have invented a new, original, and ornamental Design for an Elastic Web Fabric, of which the following is a specification, reference being had to the accompanying drawing forming a part thereof.

Fig. 1 is a top plan view of the fabric showing my new design; and

Fig. 2 is a side elevation thereof.

The design consists of an elastic web fabric having a multicolor leno stripe intermediate its opposite edges, the stripe consisting of short sections of solid colors, each color contrasting with that of the adjacent sections and giving a box-like appearance to the stripe as shown. The lining on the drawing is intended to represent color contrasts rather than specific colors.

I claim:

The ornamental design for an elastic web fabric, substantially as shown and described.

NORMAN E. RANDALL.
